UNITED STATES PATENT OFFICE.

FRANK FITCHETT, OF CALGARY, ALBERTA, CANADA, ASSIGNOR OF ONE-HALF TO
PERCY DOUGLAS McLAREN, OF CALGARY, ALBERTA, CANADA.

UNDERREAMER.

1,197,471.

Specification of Letters Patent. Patented Sept. 5, 1916.

Application filed April 4, 1916. Serial No. 88,840.

To all whom it may concern:

Be it known that I, FRANK FITCHETT, a citizen of the United States of America, and resident of the city of Calgary, in the Province of Alberta, Dominion of Canada, have invented certain new and useful Improvements in Underreamers, of which the following is the specification.

This invention relates to improvements in under reamers and the objects of the invention are to so control the bits of the reamer that they are automatically expanded into the operative position, to facilitate in removing the bits in case of repair or renewal, to simplify the construction and overcome the defects generally found in the several parts of the reamers at present in use whereby strength and durability are provided and the liability of breakage is greatly decreased or almost entirely obviated.

With the above objects in view the invention consists essentially of the improved construction particularly described and set forth in the following specification and accompanying drawings forming part of the same.

In the drawings, Figure 1 is a longitudinal section of the improved under reamer showing the bits expanded in a working position. Fig. 2 is a longitudinal section of the improved under reamer showing the same being extracted from a bore with the bits in a closed or inoperative position. Fig. 3 is a transverse section along the line 3—3 of Fig. 1.

Like characters of reference refer to like parts in the several figures.

Referring to the drawings, A represents the improved under reamer comprising the mandrel 2 making threaded engagement at the upper end with the shank B to which rotary motion may be applied in any convenient and suitable manner. The mandrel 2 is provided with an enlarged central bore 3 which extends partially therethrough and communicates at its lower end with a reduced central bore 3^a forming therewith a substantial shoulder 14, the lower end of the reduced bore communicating with the chamber 4 in the lower end of the mandrel. This chamber is of unique construction and is inclosed at the upper end by a substantially conical wall 5 connected by a tapered or conical wall 6 with a substantially cylind-

rical wall 6^a, the lower end of which is beveled as shown at 7, while the lower end of the mandrel terminates in a shoulder 23, the object of which will be made clear hereafter. It will be clearly seen that the conical wall 5 and the tapered end 7 of the chamber 4 are disposed at substantially the same angle so that they are in alinement. This chamber is provided with a transversely extending recess 18 closed at one end by the wall 18^a, the other end being partially closed toward the top by the wall 18^b, both of which walls are provided with outlet conduits 20, while the lower end of the wall 18^b is provided with an orifice 19 through which a key 15 may be inserted into the said recess.

A plunger rod 11 slidably operates in the enlarged and reduced bores 3 and 3^a having its upper end threaded and provided with a nut 13^a engaging with a washer 13 which coacts with the upper end of a spiral spring 12 surrounding the upper portion of the plunger and having its lower end engaging with the shoulder 14 while the lower end of the plunger is made substantially square and provided with a slot 15^a engaging the key 15. The key 15 is designed to operatively secure the bits 1 in position and to this end the upper end of the bits are provided with orifices 17 therethrough adapted to engage the key, the bits being adapted to coact at their center point 16 about which they are capable of being rotated.

The upper ends of the bits are tapered and formed with recessed portions 1^a adapted to embrace the lower squared end of the plunger rod 11, and when the bits are in a non-operative position the outer faces of the said tapered ends are adapted to lie parallel with each other and snugly engage the parallel walls 6^a of the chamber 4, the bits being provided intermediate of their ends with shoulders 22 designed to abut with the lower end 23 of the mandrel and being further provided with shoulders 24 adapted to coact with the lower beveled end of the shoe 21 of the casing C.

The assembly of the reamer will be readily understood from the foregoing description.

When the reamer is in use the shank B is threaded on the mandrel 2 whereupon the bits 1 are inserted into the chamber 4 and when the orifices 17 register with the orifices 19 the key 15 is inserted. The bits 1 are

now inserted in the casing C and it will be seen that in this position the plunger 11 is displaced downwardly compressing the spring 12, and when the mandrel has been passed through the casing C so that the bits 1 project beyond the shoe 21 of the said casing the spring 12 exerting a pull on the plunger 11 forces the same upwardly and pulls the upper tapered ends of the bits 1 into engagement with the conical wall 5 and tapered edge 7 of the chamber 4 forcing the bits laterally outwardly at their lower ends to engage the periphery of the hole which is being under reamed.

15 It will be noticed that when the bits 1 are expanded the key 15 is drawn toward the upper end of the recess 18 and the said key cannot in any way become displaced since its longitudinal motion is limited by the end walls 18 and 18^b of the said recess. In withdrawing the reamer from a hole when the operation of under reaming has been completed the beveled end of the shoe 21 engages with the shoulders 24 closing the bits 1 toward each other and displacing the plunger 11 downwardly so that the bits assume a position shown in Fig. 2, and it will be again noticed that the key 15 cannot become displaced while passing through the casing C since if there were any tendency of its working through the orifices 19 it would be prevented from so doing by the walls of the casing.

30 As many changes could be made in the above construction and many apparently

widely different embodiments of my invention, within the scope of the claim, constructed without departing from the spirit or scope thereof, it is intended that all matter contained in the accompanying specification and drawings shall be interpreted as 40 illustrative and not in a limiting sense.

What I claim as my invention is:

An under reamer comprising a mandrel having a central bore and provided at the lower end with a chamber inclosed at the upper end by conical walls and at the lower end by a cylindrical wall having a beveled lower edge formed in alinement with the upper conical wall and having a transversely 45 extending recess therein closed at one end and partly open at the other end, a plunger slidably operated in the bore having a square lower end and an orifice therethrough, bits provided with square recesses 50 on the upper ends thereof adapted to embrace the square end of the plunger and having orifices therethrough designed to register with the orifice in the plunger, a key engaging with the said orifices and designed to be located in the recess in the said chamber and resilient means adapted to displace the plunger upwardly to actuate the bits laterally into an operative position.

In witness whereof I have hereunto set 65 my hand in the presence of two witnesses.

FRANK FITCHETT.
